STRETCHING OF FILAMENTS OR THREADS

Filed July 17, 1943

FIG. I

28 FIG. 2

FIG. 3

FIG. 4

UNITED STATES PATENT OFFICE

2,402,228

STRETCHING OF FILAMENTS OR THREADS

Thomas Jackson and Thomas Barnard Frearson,
Spondon, near Derby, England, assignors to
British Celanese Limited, London, England, a
company of Great Britain

Application July 17, 1943, Serial No. 495,094
In Great Britain July 20, 1942

13 Claims. (Cl. 57—35)

1

This invention relates to improvements in the stretching of filaments or threads and in particular to the operation of stretching filaments or threads in the presence of a softening medium in order to improve their properties, and particularly their tensile strength. Such operations are particularly applicable to the treatment of materials of cellulose acetate or other derivative of cellulose.

U. S. Patents Nos. 2,142,909 and 2,118,856 describe operations of this kind in which steam, or hot water, or a liquid containing an organic solvent or softening agent for the substance of the filaments or threads to be stretched is used as a softening medium for enabling the stretch to be imparted. U. S. Patent No. 2,276,394 describes a method of initiating stretching operations of this kind by varying the degree of stretch applied to the filaments or threads inversely with and under the control of the tension in the material as the softening medium is initially applied and as the tension falls in consequence of the application of the softening medium. In the operations specifically described in the several specifications mentioned above, the process is applied to a number of threads, which are collected after stretching by means of a corresponding number of winding devices arranged in the form of a creel.

It has been found that advantages may be obtained, particularly in respect of the initiation of the stretching operation, by taking up the threads after they have been stretched by means of a twisting and winding device which collects the threads as fast as they are fed to it and twists them as they are so collected. This is particularly advantageous in the initiation of the stretching operation because, as the softening medium is applied to the threads and the stretching of the threads is initiated the twisting and winding devices may be arranged to take up the threads at an increasing rate as the softening and increase of stretch proceed. Indeed, the tension applied by the twisting and winding device may be utilised to bring about stretching to a degree which increases as the softness of the threads increases during the initial application of the softening medium, and when the stretch has been brought, in this manner, up to or nearly up to the degree desired, the threads may be placed under the positive control of stretching means such as rollers, which thereafter accurately determine the degree of stretch imparted and feed the threads to the twisting and winding device by which they are then collected. Before the application of the positive control, the ten-

2

sion applied to the thread by the twisting and winding device extends back to the softened part of the thread, so as to bring about the stretch, but after the positive control has been applied, this tension reaches back only to the positive control means, at which the thread is set, so that stretching is no longer effected by the tension applied by the twisting and winding device, but only by the positive control means.

10 The use of twisting and winding devices to collect the threads after they have been stretched enables the threads to be handled individually from one end of the operation to the other, and in particular enables an end that is broken down in the course of the operation to be re-established without disturbing other threads being treated simultaneously. For this purpose, individual chambers, one for each thread, may be provided, in which the softening medium is applied to the 15 thread and in which stretching of the thread takes place.

20 When, as is preferable, the softening medium is under pressure in a chamber through which the thread passes in order to be stretched, provision may be made to prevent rapid flow of the softening medium in a direction opposite to the direction of travel of the thread as it enters the chamber, and also to reduce leakage of the softening medium. Thus, as described in U. S. Patent 25 No. 2,142,909 the thread may reach the stretching chamber through a feed chamber containing forwarding rollers for the thread and supplied with air or water under pressure. The air or water chambers thus provided may also be individual chambers adapted to serve single threads, and may be formed integral with the individual stretching chambers, the two together constituting a single unit. Where steam is employed as the softening medium and the two chambers are 30 formed as a single unit, it is desirable that the partition between the chambers should be arranged to prevent rapid conduction of heat from the steam chamber to the feed chamber preceding it. For this purpose the partition may be of 35 substantial thickness and may be formed hollow for the passage of cooling medium. In order to facilitate initial threading-up through the partition, a tunnel of substantial cross-section may be provided for the passage of the thread, the tunnel 40 being closed at one or both ends by means of a plate, having only a small orifice therein for the passage of the thread.

45 Instead of providing a feed chamber as described above, the stretching chamber may be 50 provided, as described in U. S. application S. No.

472,460, filed January 15, 1943, with an injector device for the feeding of the thread into the stretching chamber, the thread being carried into the chamber by a jet of inert fluid, e. g. water, supplied under a pressure substantially exceeding that of the softening fluid in the stretching chamber. The softening fluid supplied to the chamber may assist the action of jet, by being introduced through an annular nozzle surrounding the injector nozzle through which the jet carrying the thread passes, and use may further be made of this feature for threading the thread initially through the injector. For the latter purpose, provision may be made to supply compressed air temporarily through the annular nozzle, so as to induce a suction in the injector nozzle to draw the end of the thread into the chamber.

The threading-up of the thread through the apparatus from the source of supply to the take-up packase may be completed before the apparatus is set in motion and before stretching begins. This is made possible by the fact that a twisting and winding device will collect the thread reaching it at a low rate or at a high rate without any adjustment of the spindle speed, the thread collected at a low rate merely being more highly twisted than that collected at the high rate. Thus, after threading-up has been effected on the stationary apparatus, the input to the stretching chamber, e. g. pairs of rollers, may be started and the take-up bobbin caused to rotate so as to collect, without stretching, the unsoftened thread supplied to it at a low rate. The supply of softening agent to the stretching chamber may be then turned on, and as the softness of the thread within the stretching chamber increases, the tension applied by the twisting and winding device stretches the thread to an increasing degree, and the stretched thread is collected on the bobbin. Finally, when the softness of the thread has reached a stage where the stretch imparted by the tension applied by the take-up device approaches the desired stretch, the output control of the stretching means may be put into operation so that stretching takes place at a constant and definite rate.

For the purpose of starting the rotation of the take-up bobbin, the bobbin may be mounted on an already rotating spindle but prevented from rotating therewith by means of a brake. Individual clutch means may be provided in the drive to the input rollers, and the brake applied to the take-up bobbin may be under the same control as the clutch so that rotation of the bobbin and rotation of the input rollers may be started simultaneously. Since it is desirable to apply the softening medium, and also the fluid in the chamber preceding the softening chamber, as soon as possible after feeding of the thread has started, valves for the supply of these media may also be under the same control as the input clutch and the bobbin brake, and adapted to operate a little later by a further movement of the control. Similarly, the output rollers of the stretching device may be under the same control and adapted to be brought into operation thereby later still by moving the control right home.

Ring-twisting devices are suitable for use as the twisting and winding devices employed for the purpose of the present invention, though other twisting and winding devices, such as cap-spinning devices and flyer-spinning devices may

5 be employed. Ring-twisting devices are particularly advantageous as enabling large packages of yarn to be formed without involving the use of heavy rotating parts which would in practice limit the spindle speed of the device.

The invention may be generally applied, by the selection of a suitable softening agent, to the stretching of materials in the form of threads. It is particularly applicable to the stretching of threads consisting of continuous filaments of organic derivatives of cellulose such as the cellulose esters, e. g. cellulose acetate, formate, propionate or butyrate, mixed esters, e. g. cellulose acetate-propionate and acetate-butyrate, and cellulose ethers, e. g. ethyl and benzyl cellulose.

By way of example two forms of apparatus according to the present invention will now be described in greater detail with reference to the accompanying drawing in which

Figure 1 is a side elevation of one form of apparatus,

Figure 2 is a sectional side elevation and

Figure 3 is a front elevation of a detail of Figure 1, and

Figure 4 shows a modification of the detail shown in Figures 2 and 3.

The apparatus shown in Figures 1 to 3 is in the form of a machine adapted for the stretching and collecting of several ends 1, say 6 or 12, and is provided with a corresponding number of ring-twisting spindles, of which one is shown at 2 in Figure 1, arranged in line along the front of the machine, the rings 3 being mounted on a common rail 4, and the spindles 2 on a common rail 5 in the manner usual in ring-spinning machines. The spindles 2 are driven by means of whorls 6 and belts 7, so as to rotate the take-up bobbins 8, mounted on the spindles 2. Each spindle, however, is provided with an individual bobbin brake 9, by means of which the bobbin 8 may be checked, and prevented from rotating with the spindle 2.

Behind and above each ring spindle 2 is disposed a stretching unit comprising an input roller 10, a feed chamber 11, a stretching chamber 12 and an output roller 13. The feed chamber 11 and stretching chamber 12 are integral with one another, being formed from a box 14 divided longitudinally into the two sections 11, 12 by means of a partition 15 about 2" in thickness, the length of the feed chamber 11 from end wall to partition being about 6" and that of the stretching chamber 12 about 10". The end wall of each feed chamber is provided with disc or plate 16 having a small circular aperture for the entry of the thread 1 to be stretched and the end wall of the stretching chamber is similarly provided with a plate 17 having a small hole for the exit of the thread 1. The thread 1 passes from the feed chamber 11 to the stretching chamber 12 through a passage 18 of substantial width extending through the partition 15, the end of the passage 18 nearest the stretching chamber 12 being closed by means of a plate 19 having only a small hole therein for the thread 1 to run through. The partition 15 is formed hollow and through the cavities 20 therein cooling water can be circulated.

Steam is supplied to the stretching chamber 12 through two small orifices 21, one in each side wall, each orifice 21 being in the form of a plain vertical slot about $\frac{1}{8}$ " wide and $\frac{1}{8}$ " long. These orifices and the passages 22 supplying them are disposed in the side walls close to the partition 15 between the two chambers 11 and 12.

Water under pressure is supplied to the feed chamber 11 through two larger openings 23, one in each side wall close to the partition 15, the openings 23 being in the form of vertical slots $1\frac{1}{2}$ " long by $\frac{1}{4}$ " wide. The passages 24 in the walls of the feed chamber leading to the slots 23 are so formed as to direct the water entering the chamber 11 through the slots 23 towards the partition 15 between the feed chamber 11 and the stretching chamber 12. The box 14 constituted by the feed chamber and stretching chamber is provided with a single lid 25 covering the two chambers and secured in position by means of a quick-releasing clamping device in the form of a stirrup 26 whose ends hook over pins 27 projecting from the sides of the box, and a screw 28 passing through the top of the stirrup 26 and engaging a boss 29 on the lid.

Steam is supplied to all the stretching chambers 12 of the machine, and water under pressure to all the feed chambers 11, from two headers 30 and 31 respectively running parallel to the length of the machine beneath the series of feed and stretching chambers 11, 12. The pressure in the chambers 11, 12 is controlled by controlling the pressure in the two headers, the flow of steam to the steam header 30 being under the control of the pressure in the steam header and the flow of water to the water header 31 under the control of the pressure in the water header, for example in the manner described in U. S. Patent No. 2,276,364. The headers 30, 31 are connected to the feed and stretching chambers by connections 22, 24, 32 and 33 of substantial cross-section so as to minimise the pressure drop in these connections, and valves 34, 35 for the control of the steam and water respectively are fitted in the connections.

The feed chamber 11 contains a pair of rollers 36, 37 between which the thread 1 to be stretched passes, the lower roller 36 being a mild steel roller and the upper roller 37 being a heavy rubber-covered roller carried in a plain slot bearings and held in contact with the lower roller by spring loading. The two rollers 36, 37 are positively geared together by gears 38 and the lower roller 36, whose shaft 39 extends through the wall of the feed chamber 11, carries a sprocket 40 and is driven from a sprocket 41 mounted on a driving shaft 42 running the length of the machine.

Preceding the feed chamber 11, that is to say on the side thereof remote from the stretching chamber 12, is the input roller 10, freely mounted on a shaft 43 parallel to the length of the machine and driven from the same sprocket 41 on the driving shaft 42 as the roller 36, by means of a chain 45 passing round the three sprockets 40, 41, 44. A nip roller 46 is provided to engage with the input roller 10, being carried by an arm 47 pivoted in such a manner that the weight of the nip roller 46 normally rests on the input roller 10 but may be lifted therefrom when desired as shown in dotted lines towards the left of Figure 1. The sprocket 41 driving the input roller 10 and the roller 36 is secured to the driving shaft 42 on which it is mounted by means of a clutch 48, which can be engaged or disengaged by an operative standing in front of the machine, in the manner hereinafter to be described. The input roller 10 and the roller 36 are of the same diameter, and the sprockets 40, 44 by which they are driven are provided with such numbers of teeth that the roller 36 rotates about 1% faster than the input roller 10. The shafts 43 and 42

on which the input roller and the sprocket 41 are mounted are common to the several units along the length of the machine.

Thread 1 is supplied to the several units of the machine from bobbins 50 mounted in a creel 51 at the back of the machine each thread being drawn over the end of the cone or bobbin, through a tension device 52 in the form of two discs spring-pressed together, and thence over a guide roller 53 disposed at the back of the machine level with the input and output orifices 16, 17 of the feed chambers 11 and stretching chambers 12 of the machine.

Following the stretching chambers 12, i. e. between them and the row of ring spindles 2, is an output shaft 55 carrying the series of output rollers 13, one for each spindle 2 and stretching chamber. The output rollers 13 are fixed to the output shaft 55 and, when the machine is in operation, these rollers are constantly rotating. The thread 1 leaving the stretching chamber 12 passes over the corresponding output roller 13 and is pressed against it by means of a nip roller 56 carried on an arm 57 which is pivoted so that the nip roller 56 can be removed from contact with the output roller 13. The output roller 13 is disposed immediately above the corresponding ring spindle 2 so that the thread 1 passes vertically downwards from the output roller 13 to the balloon guide 58 of the ring spindle 2. On the arm 57 carrying the nip roller is secured a hooked guide 59 which, when the nip roller 56 is in engagement with the output roller 13, lies beneath the thread 1 proceeding from the stretching chamber 12 to the output roller 13. When the nip roller 56 is pivoted away from the output roller 13, however, the hooked guide 59 engages the thread 1 and lifts it clear of the output roller 13 so that the thread 1 proceeds directly from the stretching chamber 12 to the hooked guide 59 and from the hooked guide 59 to the balloon guide 58 of the ring spindle 2 as shown in dotted lines on the right of Figure 1.

Control of the several parts of the device is effected in properly timed relationship by means of a common control member 61 in the form of a simple foot-operated lever below the spindle rail 5. This member controls the brake 9 on the ring spindle 2, the nip roller 56 and guide 59 which co-operate with the output roller 13, the steam and water valves 34, 35 and the clutch 48 through which the input 10 is actuated. For this purpose the pedal 61 is connected by means of one rod 62 to the spindle brake 9 and the lever 57 carrying the output nip roller 56, and by another rod 63 to a shaft 64 running from front to rear of the machine and controlling the steam and air valves 34, 35 and the input clutch 48. The first rod 62 passes through a lever 65 forming an extension of the brake 9 for the bobbin 8, and a pair of springs 66 mounted on the rod 62, one above and one below the brake lever 65, are held in engagement with the brake lever by means of two collars 67 on the rod, so that the rod 62 acts upon the brake 9 through one or other of the springs 66. The upper end of the rod 62 passes through a forked lever 68 constituting an extension of the pivoted lever 57 carrying the output nip roller 56, and acts on the levers 68, 57 through a spring 69 retained by a collar 70 at the end of the rod 62. The rod 63, pivoted at its lower end to the foot-operated lever 61, is connected at the upper end to the end of a crank 71 on the shaft 64 so that rising or falling of the rod 63 turns the shaft 64. The shaft 64 carries a cam

73 having two cam grooves 74 which act on the ends of two rocker levers 75, the other ends of the rocker levers 75 actuating the two piston valves 34, 35 which control the flow of steam and water from the headers 30, 31. On the end of the shaft 64 opposite to the crank 11 is a further cam 76 adapted to act on a forked lever 77 controlling the clutch 48 through which the input roller 10 is driven. Thus, depression of the foot-operated lever 61 first releases the brake 9 holding the bobbin 8 and later brings the output nip roller 56 into operation by means of one rod connection 62, and opens the steam and water valves 34, 35 and operates the input clutch 48 by means of the other rod connection 63.

In starting up the apparatus an end of thread 1 is drawn from a bobbin 58 mounted in the supply creel 51, is passed through the tension device 52 and over the guide roller 53 associated with the creel, and is passed between the input roller 10 and its nip roller 46, the nip roller 46 being lifted for this purpose. The thread 1 is then threaded through the feed chamber inlet orifice 16, through the aperture 19 in the partition 15 between the feed chamber 11 and stretching chamber 12, and out through the stretching chamber outlet orifice 17. The cover 25 is then secured in place by means of the quick-release clamp 26—28. The thread 1 is then led over the output roller 13, through the guide 59 mounted on the arm 57 carrying the output nip roller 56, down to the balloon guide 58 of the ring-spinning device 2 and thence through the traveller of the ring-spinning device to the take-up bobbin 8. During these operations the machine may be either stationary or running, and in the latter case the input roller 10 will be de-clutched from the driving shaft 42, the take-up bobbin 8 will be braked, and the output roller 13 will be rotating idly with the thread 1 passing to the ring spindle 12 out of contact with it. To begin the stretching operation the foot-operated lever 61 is depressed and the brake 9 on the take-up bobbin 8 is thereby first released. Immediately afterwards the clutch 48 driving the input roller 10 of the machine is engaged so that the thread 1 is drawn from the creel 51 and fed through the feeding and stretching chambers 11, 12 to the take-up bobbin 8. At the same time the steam and water supplies to the stretching chamber 12 and the feed chamber 11 are turned on through the valves 34, 35 and softening of the thread 1 as it runs through the stretching chamber 12 takes place. The softening of the thread 1 and the tension applied to it by the rotating take-up bobbin 8 have the effect of causing the thread 1 to be stretched, the degree of stretch increasing steadily as the stretching chamber 12 becomes filled with steam. Within a very short time the degree of stretch approaches that required, say 10-1, and at this stage the foot-operated lever 61 is depressed further so as to bring the output nip roller 56 into contact with the output roller 13. At the same time the guide 59 on the lever 57 allows the thread 1 to come into contact with the output roller 13 so that the thread is nipped against the output roller 13 and is driven thereby. The degree of stretch is now accurately determined by the relative speeds of the input roller 10 and the output roller 13 and the ring spindle 2 takes up the stretched thread 1 as fast as it is delivered by the output roller 13. At this stage, in order to distinguish the unstretched and partly-stretched thread wound on the bobbin 8 at the beginning of the operation from the fully-

stretched thread, a short length of distinctive yarn is fed to the bobbin 8 with the stretched thread so as to be twisted therewith and wound on the bobbin. This yarn binds the incompletely-stretched thread on the bobbin so that during subsequent unwinding operations the incompletely-stretched thread does not unwind and is left on the barrel of the bobbin, so that it cannot be mixed with the fully-stretched thread. Stretching and winding of the thread then proceeds until the bobbin 8 is full.

In Figure 4 is shown a sectional side elevation of a form of stretching chamber which may be employed instead of that shown as a detail in Figure 2. The chamber is constituted by a hollow cylinder 80 over the left-hand end of which (the input end) is screwed a cap 81 into which in turn are screwed two plugs 82, 83. The plug 82 comprises a nozzle portion 84 which enters an aperture 85 in the closure 81, the external shape of the nozzle 84 and the shape of the aperture being such as to form between them a converging annular space connected to a larger annular space 86 to which steam is supplied through a passage 87. The plug 83, which screws in behind the plug 82, also comprises a nozzle 88 and forms, between itself and the plug 82, an annular space 89 to which water is supplied through a passage 90. The other end of the cylinder 80 contains a plug 91 in which is formed an outlet orifice 92.

The passages 87, 90 are connected to the valves 34, 35 respectively, described with reference to Figures 1 to 3. In addition, however, compressed air may be supplied to the passage 87 for the purpose of threading up. In order to thread up, the plug 81 is removed, compressed air is supplied to the passage 87, and the end of the thread 1 is passed through the nozzle 88. The suction induced in the nozzle 84 by the flow of compressed air from the annular space 86 draws the thread into and through the nozzle 84 and blows it through the large aperture left by the removal of the plug 81. The compressed air is then turned off, the thread is threaded through the orifice 92 in the plug 91 and the plug is then screwed into place in the outlet end of the cylinder 80. The thread is then taken, as previously described, over the guide 59, and through the balloon guide 58, and is attached to the bobbin 8. The stretching operation is then started as previously described with reference to Figures 1 to 3, steam instead of compressed air being now supplied through the passage 87. In this arrangement the steam entering the cylinder 80 through the aperture 85 outside the nozzle 84, and the water entering through the nozzle 88, draw the thread from the input roller 10 and make unnecessary the provision of the rollers 36, 37.

Having described our invention, what we desire to secure by Letters Patent is:

1. Apparatus for the stretching of threads in the presence of a softening agent adapted to facilitate stretching, said apparatus comprising a stretching chamber to contain the softening agent, means for feeding the thread into said chamber, means for withdrawing the thread from said chamber at a rate faster than that at which it is fed into said chamber, a twisting and winding device adapted to collect the thread as fast as it is delivered to said device and to twist the thread as it is so collected, and means for nullifying the action of the withdrawing means on the thread at the beginning of the stretching operation so as to permit the twisting and winding

device to act as withdrawing means and to initiate the stretching of the thread.

2. Apparatus for the stretching of threads in the presence of a softening agent adapted to facilitate stretching, said apparatus comprising a stretching chamber to contain the softening agent, means for feeding the thread into said chamber, a rotatable roller for withdrawing the thread from said chamber at a rate faster than that at which it is fed into said chamber, a nip roller for pressing the thread into engagement with said rotatable roller, a twisting and winding device adapted to collect the thread as fast as it is delivered to said device and to twist the thread as it is so collected, and means for raising said nip roller from said rotatable roller so as to nullify the action of the withdrawing means on the thread at the beginning of the stretching operation and to permit the twisting and winding device to act as withdrawing means and to initiate the stretching of the thread.

3. Apparatus for the stretching of threads in the presence of a softening agent adapted to facilitate stretching, said apparatus comprising a stretching chamber to contain the softening agent, means for feeding the thread into said chamber, means for withdrawing the thread from said chamber at a rate faster than that at which it is fed into said chamber, a twisting and winding device adapted to collect the thread as fast as it is delivered to said device and to twist the thread as it is so collected, means for nullifying the action of the withdrawing means on the thread at the beginning of the stretching operation so as to permit the twisting and winding device to act as withdrawing means and to initiate the stretching of the thread, and common control means for the twisting and winding device, the feeding means, the withdrawing means and the supply of softening agent to the stretching chamber, said control means being adapted to actuate the various elements in timed sequence at the beginning of the stretching operation.

4. Apparatus for the stretching of threads in the presence of a softening agent adapted to facilitate stretching, said apparatus comprising a stretching chamber to contain the softening agent, means for feeding the thread into said chamber, a rotatable roller for withdrawing the thread from said chamber at a rate faster than that at which it is fed into said chamber, a nip roller for pressing the thread into engagement with said rotatable roller, a twisting and winding device adapted to collect the thread as fast as it is delivered to said device and to twist the thread as it is so collected, means for raising said nip roller from said rotatable roller so as to nullify the action of the withdrawing means on the thread at the beginning of the stretching operation and to permit the twisting and winding device to act as withdrawing means and to initiate the stretching of the thread, and a common control means for the twisting and winding device, the feeding means, the nip roller and the supply of softening agent to the stretching chamber, said control means being adapted to actuate the various elements in timed sequence at the beginning of the stretching operation.

5. Apparatus for the stretching of threads in the presence of a softening agent adapted to facilitate stretching, said apparatus comprising a plurality of stretching chambers to contain the softening agent, means for feeding a single thread into each of said chambers, means for withdrawing the thread from each of said chambers

at a rate faster than that at which it is fed into each of said chambers, a twisting and winding device for each chamber adapted to collect the thread as fast as it is delivered to said device and to twist the thread as it is so collected, and means for nullifying the action of the withdrawing means on the thread at the beginning of the stretching operation so as to permit the twisting and winding device to act as withdrawing means and to initiate the stretching of the thread.

6. Apparatus for the stretching of threads in the presence of moist steam under pressure, said apparatus comprising a feed chamber, a stretching chamber to contain the moist steam, forwarding rollers within said feed chamber for feeding the thread into said stretching chamber, means for supplying fluid under pressure to said feed chamber, means for withdrawing the thread from said stretching chamber at a rate faster than that at which it is fed into said stretching chamber, a twisting and winding device adapted to collect the thread as fast as it is delivered to said device and to twist the thread as it is so collected, and means for nullifying the action of the withdrawing means on the thread at the beginning of the stretching operation so as to permit the twisting and winding device to act as withdrawing means and to initiate the stretching of the thread.

7. Apparatus for the stretching of threads in the presence of a softening agent adapted to facilitate stretching, said apparatus comprising a stretching chamber to contain the softening agent, means at the inlet of said chamber for projecting a jet of fluid into said chamber in order to carry the thread into said chamber, means for withdrawing the thread from said chamber at a rate faster than that at which it is fed into said chamber, a twisting and winding device adapted to collect the thread as fast as it is delivered to said device and to twist the thread as it is so collected, and means for nullifying the action of the withdrawing means on the thread at the beginning of the stretching operation so as to permit the twisting and winding device to act as withdrawing means and to initiate the stretching of the thread.

8. Apparatus for the stretching of threads in the presence of a softening agent adapted to facilitate stretching, said apparatus comprising a stretching chamber to contain the softening agent, means for feeding the thread into said chamber, an annular nozzle for the introduction of softening agent into said chamber, said annular nozzle surrounding the inlet for the thread into said chamber, means for withdrawing the thread from said chamber at a rate faster than that at which it is fed into said chamber, a twisting and winding device adapted to collect the thread as fast as it is delivered to said device and to twist the thread as it is so collected, and means for nullifying the action of the withdrawing means on the thread at the beginning of the stretching operation so as to permit the twisting and winding device to act as withdrawing means and to initiate the stretching of the thread.

9. Apparatus for the stretching of threads in the presence of a softening agent adapted to facilitate stretching, said apparatus comprising a stretching chamber to contain the softening agent, means for feeding the thread into said chamber, means for withdrawing the thread from said chamber at a rate faster than that at which it is fed into said chamber, a ring-spinning device adapted to collect the thread as fast as it

11

is delivered to said device and to twist the thread as it is so collected, and means for nullifying the action of the withdrawing means on the thread at the beginning of the stretching operation so as to permit the ring-spinning device to act as withdrawing means and to initiate the stretching of the thread.

10. In a process for the stretching of threads in the presence of a softening medium adapted to facilitate stretching and collecting the stretched threads on thread supports to form packages of twisted yarn, drawing the thread from a source of supply and leading it to a thread support through a point on the axis of said support, rapidly rotating said support about said axis so as to wind the thread thereon as fast as it is drawn and to twist the thread by rotating the portion thereof between said point and the support in the form of a balloon, then applying the softening medium to the thread between the source of supply and said point so as to enable the tension imparted to the thread by the rotation of said balloon to stretch the thread and, when the thread is being so stretched, pressing it at a point where it has left the softening medium into engagement with a constantly rotating withdrawing roller, so as to determine accurately the degree of stretch imparted to it.

11. In the process for the stretching of threads in the presence of a softening medium adapted to facilitate stretching and collecting the stretched threads on thread supports to form packages of twisted yarn, drawing the thread from a source of supply and leading it to a thread support through a point on the axis of said support, rapidly rotating said support about its axis so as to wind the thread thereon as fast as it is drawn and to twist the thread by rotating the portion thereof between said point and the support in the form of a balloon, then applying to the thread, at successive parts of the path of the thread from said source of supply to said point, an inert fluid under pressure and fluid softening agent under pressure so as to enable the tension imparted to the thread by the rotation of said balloon to stretch the thread and, when the thread is being so stretched, pressing it at a point where it has left the softening medium into engagement with a constantly rotating withdrawing roller, so as to determine accurately the degree of stretch imparted to it.

12. In a process for the stretching of threads

12

in the presence of a softening medium adapted to facilitate stretching and collecting the stretched threads on thread supports to form packages of twisted yarn, drawing the thread from a source of supply and leading it to a thread support through a point on the axis of said support, rapidly rotating said support about its axis so as to wind the thread thereon as fast as it is drawn and to twist the thread by rotating the portion thereof between said point and the support in the form of a balloon, then applying to the thread, at successive parts of the path of the thread from said source of supply to said point, an inert fluid under elevated pressure and fluid softening agent under a lower elevated pressure so as to produce a stream of said inert fluid forwarding the thread into said softening agent and to enable the tension imparted to the thread by the rotation of said balloon to stretch the thread and, when the thread is being so stretched, pressing it at a point where it has left the softening medium into engagement with a constantly rotating withdrawing roller, so as to determine accurately the degree of stretch imparted to it.

13. In a process for the stretching of threads in the presence of a softening medium adapted to facilitate stretching and collecting the stretched threads on thread supports to form packages of twisted yarn, drawing the thread from a source of supply and leading it to a thread support through a point on the axis of said support, rapidly rotating said support about its axis so as to wind the thread thereon as fast as it is drawn and to twist the thread by rotating the portion thereof between said point and the support in the form of a balloon, then applying to the thread, at successive parts of the path of the thread from said source of supply to said point, water under elevated pressure and moist steam under a lower elevated pressure so as to produce a stream of water forwarding the thread into said moist steam and to enable the tension imparted to the thread by the rotation of said balloon to stretch the thread and, when the thread is being so stretched, pressing it at a point where it has left the moist steam into engagement with a constantly rotating withdrawal roller, so as to determine accurately the degree of stretch imparted to it.
